UNITED STATES PATENT OFFICE.

GORDON BRYAN, OF NEW BRITAIN, CONNECTICUT.

APPARATUS FOR TREATING WOOD.

1,182,633.

Specification of Letters Patent.

Patented May 9, 1916.

Application filed December 14, 1914. Serial No. 877,055.

To all whom it may concern:

Be it known that I, GORDON BRYAN, a citizen of the United States of America, residing in New Britain, in the county of Hartford and State of Connecticut, have invented a certain new and useful Apparatus for Treating Wood, of which the following is a specification.

This invention relates to the impregnation of wood with preserving or fire-proofing material in fluid condition, and consists of an apparatus adapted to force such materials into and fill the pores of the wood longitudinally thereof. This is accomplished by submitting one end of the wood to the fluid material under comparatively high pressure with the other end exposed to the atmosphere.

The apparatus comprises means for forcibly seating supports or chucks on the ends of the wood; a chamber, hermetically closeable, in which the wood is placed; a door or gate carrying one of the chucks at one end of the chamber, so constructed as to be readily and quickly manipulated, means for moving the other support, means for supplying fluid under pressure to one end of the wood, and other details of construction, as hereafter fully described, reference being had to the accompanying drawings, in which:

Figure 1 is a longitudinal vertical section of an apparatus in operative condition embodying the essential features of this invention: Fig. 2, a vertical section of the closure end of the chamber with the door in open position, on an enlarged scale, showing the door, by dotted lines, moved away from its seat; Fig. 3, a similar view of the preserving or fireproofing fluid charging end of the chamber; Fig. 4, a sectional plan view on a central horizontal line of the closure end of the chamber showing the door open; and Fig. 5, a transverse section on line 5, 5, Fig. 3.

6 designates a piece of wood, which may be timber, rectangular in cross-section, as a railroad tie, or a log circular in cross-section; 7 a chuck or movable support preferably having the walls 8 of its interior inclined as shown to receive and hold one end of the wood whose edges are correspondingly tapered; 9 designates the closure door of the chamber provided with a similar chuck or holder with inclined walls 10 and with an opening through the door at the small end

of the chuck. If logs are to be treated, the mouths of the chucks 7 and 9 will be circular and, if rectangular timbers, as cross ties are to be treated, the mouths of the chucks 60 will be rectangular as shown in Fig. 2, the size and depths of the mouth being such as are adapted to hold and seal the ends of different standard sizes of cross ties.

The closure door 9 is contained in a head 65 piece 11, preferably approximately spherical in form, said door having a rearwardly extending flange 12 resting on a lug 13 and held thereon by a screw bolt 14 which passes through a slot 15 in the flange, and is located 70 on, or about on, the vertical axis of the head thus providing for the rearward movement of the door from the seating face 16 inside the opening 17 of the head piece 11 in which position it may be swung at right angles 75 to occupy the position shown by full lines in Figs. 2 and 4, leaving a free passage to and from the chamber for the wood 6. A circular way 18 is provided to support the main part of the door 9 as it is opened and 80 closed. The door has in the outer face a sealing ring 19 of any suitable material to form a tight joint with the seating face 16. A stop 20 of any suitable material, against which the edge of the door impinges when 85 it is open, is secured by a bolt to the inside of the head piece 11.

A pipe 21 is secured to the head piece 11 by bolts 22 passing through a flange 23 on the pipe and a flange 24 on the head piece. 90 A suitable sealing joint ring 25 is provided. To locate the wood 6, as it is placed in the apparatus for its ends to properly seat in the inclined walls of the chucks 7 and 9, a guide is provided at the forward end of the 95 pipe 21 consisting of a block of wood, or other material, 26 secured in place by screws 27 and having an inclined forward end covered by a plate of metal 28 secured thereto by screws 29, 29. A similar guide piece 30, 100 provided with an inclined wearing plate 31, is secured by screws 32 in the other end of the pipe 21 and steers the inner end of the wood 6 into the mouth of the chuck 7. The lower edge of the chuck 7 rests on, or is adjacent to, the guide 30 and the upper part of the chuck is provided with a finger 33 arranged to slide in a guide way 34 at the upper part of the pipe 21. This insures the proper alignment of the tapering walls of 110 the chucks 7 and 9. Secured by screw threads to the rear end of the pipe 21 is a

rear head piece 35 which, with the pipe 21 and the other spherical head piece 11, constitutes the chamber of the apparatus.

In the operation of the apparatus it is contemplated to fill the chamber with fluid material which may be similar to that which is used to fill the pores of the wood, and to provide for this a pipe 36 having a valve 37 connects the upper side of the head piece 11 to a supply tank into which the fluid may be pumped from a tank 38 located beneath the opening 17 of the head 11. Into this tank the fluid flows from the chamber when wood is released from the door and the door 9 is opened after a charging operation. An air valve 39 also attached by a nipple 40 to the upper part of the spherical head 11 permits, when open, air to escape from the chamber while being filled. The apparatus is preferably set in inclined position, as shown in Fig. 1, with the object of retaining in the chamber as much of the fluid as possible so as to economize time etc. in filling the chamber with fluid ready for an operation when the door is closed after a log or cross-tie has been placed in treating position in the chamber. The dotted line x, x , indicates the level of fluid left in the chamber.

The movable chuck or wood holder 7 and the active fluid supply are controlled as follows: The chuck 7 is secured by screw bolts 41 to the end of a hollow plunger 42 fitted to slide in the head piece 35, a tight sliding joint being made by means of a stuffing box 43 and a gland 44 held by stud bolts 44. Surrounding the plunger 42 is a tube 45 having a flange 46 by which and the bolts 47 it is secured to a flange 48 of the head 35. A screw 49 working in the threaded end 50 of the hollow plunger 42 acts, when rotated, to cause the chuck 7 to move toward and from the chuck 10 of door 9, said screw having a stem 51 fitted to rotate in the end of the tube 45 and a stuffing box 52 and having a collar 53 bearing against thrust washers 54 placed between it and the inside of the end of the tube 45. The screw may be manipulated by any suitable means, a hand wheel 55 secured to the end of the stem 51 being shown for this purpose.

The preserving or waterproofing material is supplied under pressure through the pipe 56 which is screwed in the upper side of the tube 45, and is provided with a valve 57 for controlling the flow of the fluid. The fluid from pipe 56 surrounds the plunger 42, passes through bores 58 longitudinally in the plunger outside the screw threaded portion 50 and along around the screw 49, and through the central bore 59 in the chuck end of the plunger and so into the chuck 7.

The outer face of the door 9 has applied to it a spout 60 comprising a flange by which it is secured by screw bolts 61 to the door, and a discharge lip 62 to direct the

sap etc., exuding from the end of the wood or being forced through and from the pores, so it may, if desired, be received in a vessel other than the tank 38.

In the operation, the door 9 being open, a piece of wood, a cross tie or a log, as the case may be, is passed into the chamber, being guided into approximate position by the guides 26 and 30. The door is then swung around into dotted position shown in Fig. 2, and the chuck 7 is then set forward by the screw 49 and, sliding over the rear end of the wood, forces the forward end into the chuck 10 of the door, closing the door against its seat and finally pressing the ends of the wood into the chucks with sufficient force to insure tight sealing joints. The taper chucks and slightly taper ends of the wood tend to this result. The chamber may then be filled with the fluid through the supply pipe 36. Everything being closed and tight, the fluid under pressure is supplied by the pipe 56 and acts on the end of the wood in chuck 7, the pressure being sufficiently great to quickly force out from and replace all of the sap, etc., in the pores of the wood. The pressure for this purpose may be from 500 to 600 or more pounds per square inch, and it has been demonstrated in practice that with green wood and adequate pressure the charging process may be completed with some woods in considerably less than a minute. The fluid surrounding the wood in the chamber acts as a resisting medium to prevent injury to the wood, which may in some cases be ruptured by the internal pressure in the pores of the wood, and the fluid surrounding the wood may only be submitted to pressure, equal to that in the pores, when the wood is of such a character as to allow lateral escape of the pressure fluid through the wood; and it is to avoid disruption of the wood and loss of the charging fluid that a closed chamber is provided. In treating wood in which there would be no such lateral escape of fluid it will not be necessary to fill the chamber with a fluid nor to provide a high pressure seal for the wood at the door, provisions for resisting the end thrust then only being necessary.

It will be observed that by this construction and method of making the end seals practically the whole surface of one end of the wood is subjected to the fluid under pressure.

When it is desired to use the apparatus to treat wood in the chamber, which wood may be of any form and size, in the ordinary way without using the end chucks, then the opening in the door may be closed by a plate 63, shown in Fig. 2 in dotted lines, in the place of the spout 62; thus providing a wood treating chamber with a door adapted to open inwardly and be held against its seat by internal pressure.

I claim:—

1. An apparatus for impregnating wood, comprising a chamber, a door adapted to open inwardly at one end of the chamber, a support on the door adapted to hold one end of a piece of wood, a movable support in the chamber adapted to hold the other end of the piece of wood, means for supplying fluid under pressure to one end of the wood and means for moving the movable support and, through the medium of the wood held between the supports, forcing the door against its seat at the end of the chamber.
2. An apparatus for impregnating wood, comprising a chamber having an enlarged approximately spherical head, a door, supported on a guide-way and a central lug and adapted to turn on a stud or screw bolt on the lug, to open inwardly to a right angular position in the head at one end of the chamber, a support on the door, a movable support at the other end of the chamber, said supports being adapted to hold a piece of wood between them by its ends, means for supplying a fluid under pressure to the movable chuck, and means for forcing the movable chuck on the wood and by the wood pressing the door closed against its seat at the end of the chamber.
3. An apparatus for impregnating wood, comprising a taper chuck adapted to hold the end of a piece of wood whose edges are correspondingly tapered, a chamber in which the wood is placed and in one end of which the chuck is located, means for supplying a fluid under pressure to the end of the wood within the chuck, means for supporting the other end of the wood exposed to the atmosphere to resist the thrust of the pressure fluid on the wood, a door at the other end of the chamber carrying the supporting means and means for forcing the chuck firmly on the end of the wood and pressing the wood against its supporting means.
4. An apparatus for impregnating wood, comprising a chamber, a door, adapted to open inwardly, at one end of the chamber, an open chuck on the door, a movable chuck at the other end of the chamber, said chucks being adapted to hold a piece of wood between them by its ends, means for supplying a fluid under pressure to the movable chuck and means for forcing the movable chuck on the wood and by the wood pressing the door closed against its seat at the end of the chamber.
5. An apparatus for impregnating wood, comprising a chamber, a door, adapted to open inwardly, at one end of the chamber, an open chuck on the door, having inclined walls, a movable chuck at the other end of the chamber also having inclined walls, said chucks being adapted to hold a piece of wood between them by its ends, the edges of its ends being beveled correspondingly to the inclination of the walls of the chucks, means for supplying a fluid under pressure to the movable chuck and by the wood pressing the door closed against its seat at the end of the chamber.
6. An apparatus for impregnating wood, comprising a chamber, a door, adapted to open inwardly, at one end of the chamber, an open chuck on the door, a movable chuck at the other end of the chamber, said chucks being adapted to hold a piece of wood between them by its ends, means for supplying a fluid under pressure to the movable chuck, means for forcing the movable chuck on the wood and by the wood pressing the door closed against its seat at the end of the chamber.
7. An apparatus for impregnating wood, comprising a chamber having an enlarged approximately spherical head, a door, supported on a guide-way and a central lug and adapted to turn on a stud or screw bolt on the lug, to open inwardly to a right angular position in the head at one end of the chamber, an open chuck on the door, a movable chuck at the other end of the chamber, said chucks being adapted to hold a piece of wood between them by its ends, means for supplying a fluid under pressure to the movable chuck and means for forcing the movable chuck on the wood and by the wood pressing the door closed against its seat at the end of the chamber.
8. An apparatus for impregnating wood, comprising a chamber having an enlarged approximately spherical head with an opening for the admission of wood to the chamber and a door seat around said opening, a door, adapted to move toward and from the seat and to swing laterally when away from the seat on a center to open inwardly at right angles to its seating position in the head at one end of the chamber, an open chuck on the door, a movable chuck at the other end of the chamber, said chucks being adapted to hold a piece of wood between them by its ends, means for supplying a fluid under pressure to the movable chuck and means for forcing the movable chuck on the wood and by the wood pressing the door closed against its seat at the end of the chamber.
9. An apparatus for impregnating wood, comprising a chamber, a door, adapted to open inwardly, at one end of the chamber, an open chuck on the door, a movable chuck carried on the end of a sliding plunger at the other end of the chamber, said chucks being adapted to hold a piece of wood between them by its ends, means for supplying a fluid under pressure through the plunger to the movable chuck and a screw work-

- ing in a thread in the plunger and held stationary as regards longitudinal movement.
10. An apparatus for impregnating wood, comprising a chamber, a door, adapted to open inwardly, at one end of the chamber, an open chuck on the door having inclined walls, a movable chuck carried on the end of a sliding plunger at the other end of the chamber also having inclined walls, said chucks being adapted to hold a piece of wood longitudinally between them, the edges of the ends of the wood being beveled correspondingly to the inclination of the walls of the chucks, means for supplying a fluid under pressure through the plunger to the movable chuck, a screw working in a thread in the plunger and held stationary as regards longitudinal movement and means for forcing the movable chuck on the wood and by the wood pressing the door closed against its seat at the end of the chamber.
11. An apparatus for impregnating wood, comprising a chamber, a door adapted to open inwardly at one end of the chamber, a support on the door adapted to hold one end of a piece of wood, a movable support in the chamber adapted to hold the other end of the piece of wood, means for supplying fluid under pressure to one end of the wood, said chamber being inclined with the door end in elevated position, whereby a considerable portion of the fluid with which the chamber is charged will remain in the chamber when the door is open, and means for moving the movable support and, through the medium of the wood held between the supports, forcing the door against its seat at the end of the chamber.
12. An apparatus for impregnating wood, comprising a chamber, a door adapted to open inwardly at one end of the chamber, an open chuck on the door having inclined walls, a movable chuck carried on the end of a sliding plunger at the other end of the chamber also having inclined walls, said chucks being adapted to hold a piece of wood longitudinally between them, the edges of the ends of the wood being beveled correspondingly to the inclination of the walls of the chucks, means for supplying a fluid under pressure through the plunger to the movable chuck, a tank into which the fluid flows from the door end of the chamber, a spout on the door by means of which the fluids exuding from the discharge end of the wood may be collected, and means for forcing the movable chuck on the wood and by the wood pressing the door closed against its seat at the end of the chamber.
13. An apparatus for impregnating wood, comprising a chamber, a door, adapted to open inwardly, at one end of the chamber, an open chuck on the door, a movable chuck at the other end of the chamber, said chucks being adapted to hold a piece of wood between them by its ends, means for supplying a fluid under pressure to the movable chuck, a tank into which the fluid flows from the door end of the chamber, a spout on the door by means of which the fluids exuding from the discharge end of the wood may be collected, and means for forcing the movable chuck on the wood and by the wood pressing the door closed against its seat at the end of the chamber.

In testimony whereof, I have hereunto subscribed my name.

GORDON BRYAN.
